UNITED STATES PATENT OFFICE

ARTHUR STOCKSTROM, OF ST. LOUIS, MISSOURI, ASSIGNOR TO AMERICAN STOVE COMPANY, OF ST. LOUIS, MISSOURI, A CORPORATION OF NEW JERSEY

DESIGN FOR A GAS RANGE

Application filed August 25, 1930. Serial No. 36,762. Term of patent 14 years.

To all whom it may concern:

Be it known that I, ARTHUR STOCKSTROM, a citizen of the United States, residing in the city of St. Louis and State of Missouri, have invented a new, original, and ornamental Design for Gas Ranges, of which the following is a specification, reference being had therein to the accompanying drawing.

The accompanying drawing is a perspec-

tive view of the gas range showing my new design.

I claim:

The ornamental design for a gas range as shown.

In testimony whereof, I hereto affix my signature.

ARTHUR STOCKSTROM.
